ABSTRACT OF THE DISCLOSURE

This disclosure concerns an easy open end for pressurized containers having a removable portion defined by a score line that has a multiplicity of relatively short segments of increased resistance to severance to prevent premature or uncontrollable tear strip severance caused by high internal pressures.

This invention relates generally to containers having integral opening devices adapted to permit opening thereof without the need for a separate tool. More specifically it relates to a pressurized sealed container adapted for opening with increased safety to the consumer.

In the conventional container embodying integral opening means, the container is provided with a removable portion or tear strip defined by one or more scored lines and a pull-tab is affixed within the tear strip to facilitate removal thereof. The more common systems have a rigid tab which functions as a lever to provide a mechanical advantage to the consumer in effecting the initial score line fracture, which is the first of the two opening steps. After this, the second step, which involves tearing away of the tear strip by continuing severance of the score lines, is performed. The primary problem with increasing the ease of opening has resided in improving the ease with which initial severance may be effected. One of the more practical approaches to improving the initiation of score line fracture is that of scoring deeper in the score line adjacent the tab fastening means. The limit upon the depth to which a panel may be scored while maintaining the integrity of the package depends to a great extent upon the pressure differential to which the panel will be exposed. It is obvious that for a vacuum type container or pressurized beverage the scoring should not be as deep as for a container having an internal pressure which is approximately atmospheric.

A particular problem has been encountered with respect to packaging of pressurized beverages such as beer or soft drinks. In these packages, while the internal pressure in effect provides an assist in the initiation of score line fracture, it has frequently caused inadvertent fracture of the score line during storage. An additional and more serious problem encountered during opening of the container has been the uncontrollable acceleration of tear strip severance caused by the escaping high internal pressures being exposed to the underside of the pull-tab and tear strip. This latter reaction has been known to forcibly remove the tear strip from the hand of the person opening the container, thereby exposing the individual to the risk of cut fingers as well as exposing him and others in close proximity to the hazard of a tear strip flying uncontrolled through the air. This hazard has generally been referred to as the "rip off" tendency.

It is an object of this invention to provide a sealed pressurized container having an end which incorporates an integral opening device and is adapted for ready safe opening by the consumer without exposure to the "rip off" tendency.

It is a further object of this invention to provide a pressurized container which is free from the "rip off"

2

tendency and may be simply and economically manufactured without substantial modification to existing commercial equipment.

It is another object of this invention to provide an integral opening device which eliminates the "rip off" tendency while retaining ease of opening characteristics.

It is yet another object to provide such a pressurized container having improved resistance to accidental opening.

These and other objects will be more fully understood and appreciated from the following detailed description of the invention, on reference to the illustrations appended hereto, in which:

FIGURE 1 is a fragmentary perspective of a sealed container adapted for use with this invention;

FIGURE 2 illustrates a sectional view of a container of the type illustrated in FIGURE 1, immediately after score line severance has been initiated;

FIGURE 3 is a plan view of a container end of this invention, with the pull-tab not shown for convenience of illustration;

FIGURE 4 is a fragmentary sectional view through 4—4 of FIGURE 3;

FIGURE 5 is a plan view of a modified form of container end within the invention, with the pull-tab not shown for convenience of illustration;

FIGURE 6 is a fragmentary sectional representation of a differential scoring concept adapted for use with this invention; and

FIGURE 7 illustrates another embodiment of the invention with the pull-tab removed for convenience of illustration.

Turning more specifically to the drawings, as is shown in FIGURE 1, a container 1 has an end wall 2 provided with a removable portion or tear strip 3 which is defined by scored line or lines 4. Within the tear strip 3 at one end thereof is affixed a pull-tab 5 which is secured to the tear strip 3 by any conventional fastening means 6, such as an integral rivet, for example. The tab 5 is reinforced by one or more ribs 7 in order to facilitate its functioning as a rigid lever. In effecting initial severance of the scored line 4, the consumer grasps gripping portion 8 and raises it, thereby effecting engagement of fulcrum 9 with the end wall or panel 2. Continued upward rotation results in employment of the mechanical advantage of the lever tab to effect initial fracture of the score line 4.

FIGURE 2 illustrates the position of the pull-tab 5 at the instant immediately after initial severance. At this instant a relatively small aperture A is created. The "rip-off" tendency arises from the gas at high internal pressure attempting to instantaneously exhaust through the aperture which is inadequate in size for this purpose. What tends to occur, therefore, is that the end yields at its points of least resistance, which are the scored lines, and the uncontrolled acceleration of scored line severance occurs. As was stated above, this may result in cut fingers as well as the hazard of a tear strip flying uncontrolled through the air.

An additional problem experienced with pressurized containers having integral opening devices is that of preventing accidental severance of the scored lines by the internal pressure during storage. Although efforts have been made to provide an adequate score line residual to resist the pressure, the primary desire for increased ease of opening has prevented the use of scoring sufficiently shallow to effectively eliminate "leakers."

This invention contemplates an effective solution to the aforementioned problems by providing a multiplicity of sectors of increased resistance to severance on the scored lines. These sectors of increased resistance will prevent rapid and uncontrolled acceleration of the score line severance and will thereby prevent "rip-off." Also, these sectors will act to reinforce the end panel and re-

sist accidental score line severance. The foregoing is readily accomplished by the sectors of increased resistance, while not interfering with the more difficult stage of opening, i.e., the initiation of score line severance. The second stage of opening, the tearing away of the tear strip by continuing the previously initiated score line severance, is effectively controlled and accidental migration of the score line severance is prevented. This latter stage of opening has not proved difficult for the consumer and therefore the slight increase in the amount of applied force required to complete tear strip removal, does not result in any meaningful difference in tear strip removal characteristics and is entirely tolerable.

As the preferred form of this invention relates to pressurized containers for flowable materials, such as beer or carbonated beverages, for example, the tear strip 3 will generally be elongated to provide an elongated orifice with adequate opening for pouring and will cover a minor portion of the panel. For ease of pouring, this elongated tear strip will preferably, but not necessarily, be disposed in a generally radial direction. The term "innermost end" as used herein will refer generally to the area which contains the tab securing means and may be geometrically defined as being separated from the remainder of the tear strip by a line perpendicular to the tear strip centerline near the center thereof and intersecting the scored line at two points. In FIGURE 5, the innermost end 13 is defined by line 19 which is perpendicular to centerline 20.

In the embodiment of the invention shown in FIGURES 3 and 4 the container end has a multiplicity of segments of increased resistance in the form of score line portions which are scored to different depths thereby providing a path of varied resistance which undulates in a direction substantially perpendicular to the container end panel. While it will be appreciated that the resistance to severance is actually provided by the residual metal remaining after scoring, for convenience of discussion, reference will be made to depth of score. For sheet of substantially uniform thickness, such as is generally employed in containers, the thickness of the residual metal will, of course, be equal to the difference between the original thickness and the depth of score. Also, it will be appreciated that these idealized dimensions actually represent a depth plus or minus the tooling and metal thickness tolerances.

In FIGURE 4, the original metal thickness is $a-d$ and the normal scoring depth is $a-c$. Interrupting the score line depth $a-c$ and alternating therewith are a plurality of score line segments 10 which are scored to a depth $a-b$. The effect of these sectors is to require periodic severance of the increased residual left by scoring to a shallower depth $a-b$. While the exemplary FIGURE 4 illustrates only one scoring depth ($a-b$) deviating from the regular depth ($a-c$), it will be appreciated that where desired, two or more different scoring depths other than the regular or standard depth ($a-c$) may be employed in order to provide a gradation of resistances. In lieu of or in addition to such variations, the segments of regular depth score may also be varied to provide even greater control. This is merely a matter of choice. What is essential is that there be a plurality of sectors of one or more scoring depths disposed on the score line in alternating position with a plurality of sectors of different scoring depths. There is no critical length for any of the sectors, nor need they be of equal length. It is, however, desirable for them to be of relatively short length in order to provide refined control of the resistance to severance. In FIGURE 3, the end 2 has a multiplicity of segments 11 scored to the conventional depth and a multiplicity of segments 12 which are scored to one or more depths which are more shallow than the depth of segments 11 and are alternately interspaced between the segments 11. It is noted that the segments continue along substantially the entire scored line 4. While it is not es-

sential, it is desirable for purposes of avoidance of accidental rupture of the score line by the pressure differential across the panel, that these alternating segments continue over a major portion of the score line. Where the regular or deepest score is sufficiently shallow that accidental fracture or leakage is not of major concern, a lesser portion of the score line may be segmented and avoidance of the "rip off" tendency will still be obtained. Even where accidental fracture is not a problem and the sole purpose for placing segments of varying resistance on the score line is avoidance of the "rip off" hazard, it is generally desirable to provide these segments over a major portion of the innermost end 13, i.e., the end of the tear strip 3 to which the pull-tab 5 is affixed.

It will be appreciated that the flexibility of the system permits very fine, precise control of the opening properties and permits panel design corresponding precisely to the contemplated pressure differential across the panel. In addition to adjusting the score depths of segments 11, 12, the lengths of the respective segments may be varied. It is not necessary that the segments 11 be of equal length to the segments 12, nor is it necessary that all of the segments 12 or segments 11 be of equal length, although all of the segments should be of relatively short lengths. The end shown in FIGURE 5 has a plurality of segments at the innermost end 13 of tear strip 3 which are shorter than the segments at the outermost end 14 of the tear strip.

It will be further appreciated that the end is adapted to be made with substantially the same equipment presently used in the commercial manufacture of such ends, with only minor modifications to the tooling being required. It is also compatible with improvements presently being made to existing forms of container ends. As was shown in Henchert U.S. Patent No. 3,151,766, the ease of effecting initial score line fracture, i.e., the first opening step, may be improved by scoring the innermost end 13 of tab 5 more deeply than the remainder of the scoring. This principle may be incorporated into our end by scoring the segments 11, 12 deeper in the innermost end 13 than at the outermost end 14. For simplicity, it is preferable, but not essential, that the depth of segments 11 on the innermost end 13 differ from the depth of segments 11 in the outermost portions 14 by substantially the same amount as the corresponding differences between similarly disposed segments 12. A profile of such scoring is illustrated in FIGURE 6 with the solid line 15 representing the depth of the scoring at the innermost end 13 and dotted line 16 representing the depth of the scoring on the remaining portion of the score line.

Additional simplicity is obtained with slightly reduced control by scoring all segments 11 to the same depth and all segments 12 to the same depth, but less than the depth of segments 11.

Turning to another embodiment of the invention, FIGURE 7 shows another type of container end which has segments of increased resistance to fracture 17. These segments consist of score line portions 18 which undulate in a direction substantially coplanar with the container end panel. These abrupt changes of direction provide increased resistance to score line severance in order to prevent uncontrolled severance of the scored lines and thereby eliminate the hazard of the "rip off" tendency. These segments may preferably extend over a major portion of the innermost end 13 of the tear strip 3. It will be obvious to those skilled in the art that there may be instances where it would be desirable to combine this embodiment with the varying score line embodiment in a single end adapted for use with a pressurized container.

Throughout the discussion the terms "score lines" and "scored line(s)" have been employed interchangeably, as the principle of the invention is equally applicable regardless of whether the tear strip is considered as being bounded and defined by one score line or a number of them.

Whereas particular embodiments of the invention have been described above for purposes of illustration, it will be evident to those skilled in the art that numerous variations of the details may be made without departing from the invention as defined in the appended claims.

I claim:

1. A container end for pressurized sealed containers, comprising,
a panel portion having an elongated removable portion defined by at least one scored line,
a pull-tab affixed to one end of said removable portion, and
said scored line containing a multiplicity of relatively short segments of increased resistance to severance.
2. A pressurized sealed container comprising in combination
the container end of claim 1 wherein said segments of increased resistance are undulating score line portions, and
a container body sealingly joined to said end.
3. The pressurized sealed container of claim 2 wherein said portions undulate in a path which is substantially coplanar with the plane of said container end panel.
4. The pressurized sealed container of claim 2 wherein said portions undulate in a path which is substantially perpendicular to the plane of said container end panel.
5. The pressurized sealed container of claim 4 wherein each said segments are of relatively short length and are adjacent segments of relatively short length scored to a different depth.
6. The pressurized sealed container of claim 5 wherein alternate segments are scored to substantially equal depths.

7. The pressurized sealed container of claim 5 wherein said relatively short score line segments are disposed over a major portion of said score line.

8. The pressurized sealed container of claim 5 wherein all of said segments are of substantially equal length.

9. The pressurized sealed container of claim 5 wherein said elongated removable portion extends substantially radially over a minor portion of said container end panel and said relatively short score line segments are disposed over substantially all of said score line.

10. The pressurized sealed container of claim 6 wherein said relatively short score line segments which are of substantially equal depths are of substantially equal length.

11. The pressurized sealed container of claim 6 wherein in said alternate segments in the innermost end of said elongated removable portion are scored deeper than the respective corresponding alternate segments in the remainder of said removable portion.

12. The pressurized sealed container of claim 11 wherein in the increase in depth of score in each of said alternate segments in the innermost end of said elongated removable portion with respect to the depth of score in each of the respective corresponding alternate segments in the remainder of said removable portion is substantially equal.
